HOLDER FOR HOUSE STREET NUMBERS

Tony Robert, 5701 Southwest Freeway,
Houston, Tex. 77027

Filed Feb. 13, 1968, Ser. No. 10,564

Term of patent 14 years

(Cl. D96—12)

FIGURE 1 is a perspective view of the top, side and an end of a holder for house street numbers, showing my new design;

The broken line representation of house street numbers in FIGURES 1 and 2 are for purposes of illustration only.

I claim:

The ornamental design for a holder for house street numbers, as shown and described.
